United States Patent Office.

AARON B. HARRIS, OF MORRISVILLE, ASSIGNOR TO HIMSELF, H. D. BRYANT,
AND H. H. GATES, OF LAMOILLE COUNTY, VERMONT.

Letters Patent No. 78,963, dated June 16, 1868.

IMPROVED BUTTER-TUB.

The Schedule referred to in these Letters Patent and making part of the same.

TO ALL WHOM IT MAY CONCERN:

Be it known that I, AARON B. HARRIS, of Morrisville, in the county of Lamoille, and in the State of Vermont, have invented certain new and useful Improvements in Butter or other Tubs; and do hereby declare that the following is a full, clear, and exact description thereof, reference being had to the accompanying drawings, and to the letters of reference marked thereon.

The nature of my invention consists in the manner of fastening the cover to the tub by means of metal spring-hooks on the cover, and flanged plates, forming ratch-bars, on the tub.

In order to enable others skilled in the art to make and use my invention, I will now proceed to describe its construction and operation.

In the annexed drawings, forming part of this specification, A represents a tub; B, the cover thereto, which extends a trifle beyond the edge of the tub, and is provided with one or more metal hooks, *a a*.

These hooks are secured on the top of the cover, and bent downwards, their lower edge being bent inwards, so as to form a hook, as shown in Figure 2.

The lower end of this hook, thus formed, is slightly bevelled, so as to correspond with the bevelled flanges on the metal plates *b b*, which are secured to the upper outside edge of the tub.

The lower side of these bevelled flanges is notched in the same manner as a ratch-bar, that is, with one side of the teeth square; and the hooks *a a* are so constructed as to give or spring over these teeth, thereby preventing them from slipping off when once put on, unless so desired, when they may easily be sprung off.

Having thus fully described my invention, what I claim as new, and desire to secure by Letters Patent, is—

The metal spring-hooks *a a*, in combination with the flanged ratch-plates *b b*, for the purpose of fastening the cover to the tub, substantially as and for the purposes herein set forth.

In testimony that I claim the foregoing, I have hereunto set my hand, this 23d day of May, 1868.

A. B. HARRIS.
